R. Webster.

UNITED STATES PATENT OFFICE.

JARVIS SHERMAN WIGHT, OF BROOKLYN, NEW YORK.

VAPORIZER.

Application filed September 18, 1919. Serial No. 324,399.

To all whom it may concern:

Be it known that I, JARVIS SHERMAN WIGHT, a citizen of the United States, and resident of Brooklyn, in the county of Kings and State of New York, have invented certain new and useful Improvements in Vaporizers, of which the following is a specification.

The invention relates to a vaporizer for combustion engines.

The object of the invention is to enable the proper proportion of water to be supplied to the engine with the charge through the inlet manifold, to prevent deposition of carbon by incomplete combustion, and to remove accumulated carbon.

In order to attain successfully this object, this invention provides a control of both quality and quantity of the water vapor or steam.

Other objects of this invention will appear more fully hereinafter.

Referring to the accompanying drawings:

Fig. 1 is a vaporizer embodying the invention installed on an automobile engine.

Fig. 2 is a vertical view, partly in section.

Fig. 3 is a detail view of the valve setting and locking mechanism.

1 is a body having a top and bottom cap 2, 3. A float 4 is within the body 1 and is attached to a valve stem 5 which passes through bottom cap 3. Secured centrally to the bottom of cap 3 is a boss 6 containing a chamber 7 and a water inlet 8. A valve 9 on stem 5 operates in chamber 7 and has a seat 10 formed in the bottom cap 3 within the chamber 7. Boss 6 is adapted to be screwed into the exhaust pipe 11 or otherwise mounted so as to be heated. Leading 40 to the water inlet from the engine water jacket 13 or other source of supply is pipe 12. Pipe 23 is an air intake pipe to the body 1 either from atmosphere, or preferably from the crank case, because this air 45 is hot and also carries a considerable amount of combustible vapor. Leading from the body 1 are two pipes 14 and 15 which converge into mixing pipe 16 which in turn leads to inlet manifold 17. Pipe 14 has a 50 valve 18 to control the quantity of steam or water vapor passing therethrough and pipe 15 likewise has a valve 19 to control the quantity of water passing therethrough. Valves 18 and 19 have set screws 20 and 21 55 to maintain the proper adjustment of the

valves, when made, against vibration and accidental movement. Valve 9 has a pilot 25 integral therewith to provide for a proper seating of the valve in the case of movement from the perpendicular, of the float, which occurs when the vaporizer is applied to automobiles and when they are in operation.

The exhaust gases heat the water in chamber 7 which flows past valve 9 into body 65

1. Float 4 and valve 9 maintain the water at a constant level. Air inlet 23 permits the formation of water vapor or steam under atmospheric pressure. Valve 18 controls the quantity of water vapor or dry steam while 70 valve 19 controls the amount of water flowing into the mixing passage 16. The quality of the steam is therefore controlled by valve 19. It has been found in practice that vapor alone with air is not fully satisfactory, because the air cannot carry enough, but by supplying additional water, which can be entrained and carried along by the air and vapor, extremely satisfactory results are secured. For removing accumulations, additional water is supplied while the 75 engine is raced.

Various changes and modifications might be made in the details and arrangements of this invention and still be within the 80 scope of the appended claims.

What is claimed, is:

1. The combination with a vaporizer having a vapor chamber, of a supply passageway for an internal combustion engine 85 connected therewith, air and water intakes to said chamber, and separate water and vapor outlets from the chamber to the supply passageway.

2. The combination with a vaporizer having a vapor chamber, of a mixing passage for an internal combustion engine 90 connected thereto, air and water intakes to said chamber, means for maintaining the water in the chamber at a constant 95 level, an outlet from the chamber above the water level and one from below the water level, the said outlets communicating with the mixing passage.

3. In a vaporizer having a vapor chamber, air and water intakes to said chamber, a float in said chamber for controlling the water intake and maintaining the water level in said chamber substantially constant, a supply passageway to an internal 100

105

100

110

- combustion engine leading from said chamber above the substantially constant water level, means for passing air through said chamber and into said passageway, 5 means for heating the water to give off vapor in the chamber, means for supplying water in liquid form to said passageway, and means for controlling the amount of liquid so supplied.
- 10 4. In a vaporizer, a tank having a main chamber and a communicating auxiliary heating and valve chamber, an air inlet to the main chamber, a water inlet to the auxiliary chamber, a float controlled 15 valve between the main chamber and the auxiliary chamber to maintain the water in the main chamber at a constant level, an outlet above the water line and one below it from the main chamber communicating with a mixing passage.
- 15 5. A vaporizer comprising in combination a chamber, a water inlet for the chamber, an air inlet in said chamber, an outlet from the chamber above the normal 20 level of the water therein, a similar outlet below the water level, a regulating valve in said second mentioned outlet, and means beyond said valve for connecting said outlets.
- 25 6. A vaporizer comprising in combination a float chamber, a water inlet valve in said float chamber, a float in said chamber controlling said valve, a source of water supply connected with said valve, an air inlet to said chamber, an outlet from the chamber above the normal level of the water therein, a similar outlet below said 30 water level, regulating valves in said outlets.
- 35
- lets, and means for mixing the air and water from said outlets.
7. A charge moistening device comprising a float chamber, a water inlet valve in said float chamber, a float in said float chamber controlling said valve, means for heating the water to cause it to give off vapor in said float chamber, means for entraining particles of liquid water with the vapor to produce a mixture having greater water content than said vapor alone, means for delivering the mixture to an engine 45 and means for controlling the quantity of vapor thus admitted to the engine.
8. A charge moistening device comprising a float chamber, a water inlet valve in said float chamber, a float in said float 50 chamber controlling said valve, means for heating the water to cause it to give off vapor in said float chamber, means for entraining particles of liquid water with the vapor to produce a mixture having greater 55 water content than said vapor alone, means for controlling the quantity of liquid water so entrained, and means for delivering the mixture to an engine.
9. In a vaporizer, the combination with 60 a chamber provided with means for supplying air and water thereto, an air outlet in the upper portion of the chamber, and a water outlet in the lower portion thereof, means for connecting said outlets and for 65 controlling the proportions of air and water in the resultant mixture.

Signed at Brooklyn, in the county of Kings and State of New York, this 16th day of September, A. D. 1919.

JARVIS SHERMAN WIGHT.
